UNITED STATES PATENT OFFICE.

WALDEMAR MICHELSSEN, OF JATIBONICO, CUBA.

CENTRIFUGAL MACHINE.

1,040,373.

Specification of Letters Patent.

Patented Oct. 8, 1912.

Application filed January 27, 1912. Serial No. 673,909.

To all whom it may concern:

Be it known that I, WALDEMAR MICHELSSEN, a subject of the King of Norway, residing at Jatibonico, Cuba, have invented 5 certain new and useful Improvements in Centrifugal Machines; and I do hereby declare the following to be a full, clear, and exact description of the invention, such as will enable others skilled in the art to which 10 it appertains to make and use the same.

My invention relates to an improved centrifugal separator, and it consists in the constructions, combinations, and arrangements herein described and claimed.

15 An object of my invention is to provide an improved centrifugal separator adapted for efficient operation with either pasty mixtures, as pulp, etc., or sticky, slow-flowing materials, as massecuite, etc.

20 A further object of my invention is to provide an improved centrifugal separator in which the screening walls will be automatically maintained in an open, unclogged condition, and the material fed therealong with 25 a uniform progressive movement by gravity.

A further object of my invention is to provide an improved centrifugal separator in which the mass of material acted upon will be alternately compressed and loosened, thereby insuring a thorough and uniform 30 separating action throughout the entire mass.

In the accompanying drawings forming a 35 part of this application, and in which similar reference symbols indicate corresponding parts in the several views:—Figure 1 is an elevation, with the left-hand side in central section, illustrating one embodiment of my invention; Fig. 2 is a plan view on the 40 line 2—2 of Fig. 1; and, Fig. 3 is a section on the line 3—3 of Fig. 1.

Referring to the drawings—1 indicates a central drive shaft provided with a lower step bearing 2, and having rigidly secured 45 thereto a drive pulley 3, lower bracket 4, and upper hollow head 5. A stationarily supported feed hopper 6 communicates with the hollow head 5, and rigidly supports a step bearing 7 for the upper end of the 50 drive shaft 1; said hopper and bearing being shown provided with coöperating downwardly diverging walls 8 and 9 for causing

a uniform distribution of the material fed to the hollow head 5, and deflecting such material from the stepped upper end of the 55 drive shaft.

A series of spindles 10 are journaled at 11 and 12, respectively, into the lower bracket 4 and hollow head 5, and carry friction gears 13 at their upper ends in engagement 60 with a corresponding stationary friction gear 14 on the hopper 6. A screen receptacle comprising a perforated cylindrical wall 15 is concentrically secured to each spindle 10 by upper and lower spiders 16 and 17; said cylindrical walls being preferably provided with internal ribs 18. An independent casing 19 of imperforate material is rigidly secured to said bracket 4 and head 5 about each screening receptacle, and provided with a reentrant cylindrical partition 20 spaced concentrically about said receptacle and terminating in a downwardly-extending hopper 21; an annular shield 22 being secured to the screening receptacle for 75 loosely inclosing the upper portion of said cylindrical partition. The casing 19 and hopper 21 are provided, respectively, with outlets 23 and 24 for discharging into any desired receptacles, such as troughs or gutters. If desired, the discharge outlets from the several casings can be arranged at different radial distances from the central shaft 1, in order to permit the material from the different screening receptacles to be discharged into separate troughs.

In my improved construction, the radii of the friction gears 13 and 14 and cylindrical screening walls 15 are so proportioned that the centrifugal force produced on said cylindrical walls by axial rotation about their spindles 10, is less than the centrifugal force produced on said walls by their rotation about the central drive shaft 1. By this construction, the material under treatment 95 is compressed against the cylindrical screening walls 15 by a gradually varying centrifugal force which is the resultant of the algebraic sum of the centrifugal forces due to the simultaneous axial rotation and revolution about the central shaft 1. This resultant effective centrifugal force reaches a maximum as the cylindrical screening wall rotates past its outer position farthest from

the central drive shaft 1, and becomes negative as said wall is rotated past its inner position nearest to said central drive shaft. During repeated rotations past such inner position, the mass of material under treatment is loosened from the perforated screening wall by the preponderance of the centrifugal force due to revolution about the shaft 1 over that due to axial rotation about the spindle 10; thereby causing the loosened material to be progressively fed downwardly along the screening wall by gravity, and automatically maintaining said wall in open, unclogged condition. Upon continued rotation of the cylindrical screening wall past its inner position, the internal ribs 18 will insure the loosened material being efficiently carried along until the latter is again pressed against the screening wall by a gradually increasing centrifugal force which reaches a maximum in the outer position of said wall. It will be obvious that the internal ribs 18 can be given any desired form, and that for pulp and other nonsticky materials, said ribs may advantageously extend spirally or be inclined. By thus alternately compressing and loosening the material under treatment and automatically maintaining the screening walls in an unclogged condition, an efficient separating action will be obtained uniformly throughout the entire mass, and the capacity or output of the machine maintained at a maximum.

A spout 25 is provided for directing the material from the hollow head 5 to each screening receptacle; said spout being arranged to direct the material slightly below the upper edges of the cylindrical wall 15 and at points past the position of maximum centrifugal force on said walls, as shown in Figs. 1 and 2; thereby insuring an even and uniform distribution of the material over the perforated wall 15. The spouts 25 can be advantageously formed of copper, or other yielding material, in order that they may be conveniently bent to insure an efficient initial disposition of various different materials on the cylindrical perforated walls.

I have illustrated and described preferred and satisfactory constructions, but changes could be made within the spirit and scope of my invention.

I claim:

1. In a centrifugal separator, the combination of a drive shaft, upper and lower members secured to said shaft, a series of screening receptacles journaled in said members, independent casings of imperforate material secured to said members about said several screening receptacles, and means carried by said several casings for discharging the materials acted upon by the inclosed screening receptacles.

2. In a centrifugal separator, the combination of a drive shaft, upper and lower

members secured to said shaft, a series of screening receptacles journaled in said members, independent casings of imperforate material secured to said members about said several screening receptacles, and means carried by said several casings at different distances from said drive shaft for discharging the materials acted upon by the inclosed screening receptacles.

3. In a centrifugal separator, the combination of a drive shaft, upper and lower members secured to said shaft, a series of open-bottom, cylindrical screening receptacles journaled in said member, an independent casing of imperforate material secured to said members about each of said screening receptacles and provided with a reentrant cylindrical partition extending above the open bottom of said receptacle, and a shield secured to said receptacle for loosely inclosing the upper portion of said partition.

4. In a centrifugal separator, the combination of a drive shaft provided with a lower step bearing, a lower bracket and an upper hollow head secured to said shaft, a stationary feed hopper communicating with said hollow head, a step bearing for the upper end of said shaft rigidly supported within said hopper and provided with a downwardly diverging cap portion, spindles journaled in said bracket and head, cylindrical screening receptacles concentrically supported on said several spindles, independent casings of imperforate material secured to said bracket and hollow head about said several screening receptacles, and coöperating gears on said hopper and spindles for axially rotating said cylindrical receptacles.

5. In a centrifugal separator, the combination of a drive shaft, bearings rigidly carried thereby, a spindle journaled in said bearings, a screening receptacle provided with a perforated cylindrical wall supported concentrically on said spindle, internal ribs on said cylindrical wall, means for driving said shaft to revolve said screening receptacle thereabout, and means for simultaneously rotating said receptacle about its spindle to produce a centrifugal force at the ribbed cylindrical wall less than the minimum centrifugal force produced at said wall by the revolution of the latter about said shaft.

6. In a centrifugal separator, the combination of a drive shaft provided with a lower step bearing, a lower bracket and an upper hollow head secured to said shaft, a stationary feed hopper communicating with said hollow head, a step bearing for the upper end of said shaft rigidly supported within said hopper and provided with a diverging cap, spindles journaled at their respective ends in said bracket and head, cylindrical screening receptacles concentrically

supported on said several spindles, interior ribs on the cylindrical walls of said receptacles, and engaging gears on said hopper and spindles for axially rotating said cylindrical receptacles to produce a centrifugal force at the ribbed cylindrical walls thereof less than the minimum centrifugal force produced on said receptacle walls by the

revolution of the latter about said drive shaft.

In testimony whereof, I affix my signature, in presence of two witnesses.

WALDEMAR MICIELSEN.
